UNITED STATES PATENT OFFICE.

CARL B. DOLGE, OF WESTPORT, CONNECTICUT.

EMBALMING-BOARD.

1,109,406.

Specification of Letters Patent. Patented Sept. 1, 1914.

Application filed August 14, 1913. Serial No. 784,807.

To all whom it may concern:

Be it known that I, CARL B. DOLGE, citizen of the United States, residing at Westport, in the county of Fairfield and State of Connecticut, have invented new and useful Improvements in Embalming-Boards, of which the following is a specification.

My present invention pertains to boards or tables for the use of embalmers; and it has for one of its objects to provide a board constructed with a view to being compactly folded when not in use, and also constructed with a view to being expeditiously and easily set up and made ready for use.

Another object of the invention is the provision of an embalmer's table embodying such a construction that it is stiff and rigid, when set up ready for use, and is calculated to bear a great weight.

Another object is the provision of an embalmer's table embodying a center leg and means for automatically locking the intermediate top sections together so as to absolutely preclude any change in the position of the same.

Another object is the provision of an embalmer's board embodying such a construction and relative arrangement of parts that a body may be conveniently positioned in such manner as to assure a thorough drainage of blood and an adequate circulation of embalming fluid to all parts of the body.

Another object is the provision of an embalmer's board adapted to be adjusted to a considerable extent to suit bodies of different sizes, this with a view to obviating the necessity of a funeral director having more than one board.

Another object is the provision on an embalmer's board of means for supporting a canopy.

Other advantageous characteristics of the invention will be fully understood from the following description and claim when the same are read in connection with the drawings, accompanying and forming part of this specification, in which:

Figure 1 is a side elevation illustrating my novel board as set up ready for use; one end of the board being shown as equipped with a canopy support, and one pair of top sections being shown as supported in inclined position. Fig. 2 is a view showing the board as folded. Fig. 3 is an end elevation of the board as it appears when set up ready for use. Fig. 4 is a detail plan, partly

broken away and partly in section, showing the manner of attaching a canopy support to one frame extension. Fig. 5 is an enlarged detail view of the center leg of the board and its appurtenances. Fig. 6 is a similar view taken at a right angle to Fig. 5. Fig. 7 is an enlarged detail view illustrative of one of the latches for locking the opposed top sections together.

Similar numerals of reference designate corresponding parts in all of the views of the drawings.

Among other elements, my novel board comprises a central-transverse rod 1, and to the middle of the said rod is connected a central supporting leg 2, equipped with stays 3, pivotally connected to the leg at 4 and designed to be detachably connected to lugs 5. The lugs 5 are fixed to cross-bars 5^a which are disposed below the opposed top sections 6 and are interposed between and fixed at their ends to side frame bars 7. The said top sections 6 are fixed in suitable manner to the said side frame bars 7, 80 and at their inner ends the frame bars 7 are provided with arms 8 fixedly connected thereto and pivotally connected to the end portions of the transverse rod 1. Thus it will be manifest that when the stays 3 are 85 detached from bolts 9 on the lugs 5 and are swung down alongside the central leg 2, the inner top sections 6 and the frame bars 7 can be swung inwardly toward each other and into the position shown in Fig. 2, the transverse rod 1 serving as a center. Again when the inner top sections 6 are swung into alignment with each other, as shown in Figs. 1, 5 and 7, and the stays 3 are attached by the bolts 9 to the lugs 5, the central leg and its appurtenances will support the inner top sections 6 to such an extent that the same

will bear any ordinary weight. In the position shown in Figs. 1, 5 and 7, the inner edges of the inner top sections 6 are opposed, as are also the arms 8 on the frame bars 7, and in order to automatically lock the said top sections 6 and frame bars 7 in the said position, I provide latches, one at one side of the board and on a frame bar 7 complementary to one top section 6, and the other at the other side of the board and on one frame bar 7 complementary to the other top section 6. One of the said latches is shown in detail in Fig. 7, and by reference to the said figure it will be observed that the latch 10 is pivoted at 11 on the frame

bar 7, and is provided with a beveled head 12 and a handle or finger-piece 13, the latter extending laterally inward from the latch. It will also be observed by reference to said figure, that the outer arm of the latch is backed by a spring 14, and that at 15 in the opposite side bar 7, or rather in the horizontal portion thereof, the side bar being of right-angle form in cross-section, a seat is provided into which the beveled head of the latch is adapted to spring. From this it follows that when the top sections 6 and the frame bars 7 are alined, the latch complementary to each top section 6 will spring into the seat 15 of the other top section 6 and in that way the top sections and the frame bars 7 thereof will be locked together securely and in such manner as to preclude any flexing of the board at its middle. This is an important feature of my invention inasmuch as it contributes to the safety of the board in supporting a very heavy corpse.

Pivots connected at 16 to the outer ends of the frame bars 7 are legs 17. These legs are arranged in pairs as shown in Fig. 3, and the legs of each pair are fixedly connected together through the medium of crossed braces 18. It will also be observed that pivots connected to the frame bars 7 at the points 16 are frame extensions or bars 19. These extension bars 19 are connected with the legs 17 through the medium of struts 20 each of which comprises two sections, pivots connected at 21 and designed to be stopped in straight position or alinement by the seating of a stud 21 on one section in a notch 22 in the other section. Between each pair of legs 17 and their complementary top section 6 are arranged struts 20^a similar in construction to the struts 20 just described. By virtue of the frame construction just alluded to it will be manifest that when the struts 20 are broken the extension frame bars 19, which are preferably of angle iron can be swung down alongside the legs 17, and then by breaking or flexing the struts 20^a the extension frame bars 19 and the legs 17 can be swung into positions substantially between and parallel to the frame bars 7 and the top sections 6. This as will be readily appreciated contributes materially to the compact form into which the board can be folded for convenient carriage. It will be understood, however, that when it is desired to open and set-up the board the same can be readily accomplished by first swinging the legs 17 to a position at right angles to the frame bars 7, and then swinging the extension frame bars 19 out into alinement with the frame bars 7, and then arranging the struts 20 and 20^a in their straight locked positions as shown in Fig. 1.

Each pair of the extension frame bars 7 comprises a cross bar 23, interposed between 35 and fixed to the bars of the pair, and also

fixed on the bars of the pair at the outer ends thereof are apertured plates 24, Fig. 1, for an important purpose hereinafter set forth.

25 25 are top sections arranged adjacent 70 the top sections 6, and 26 26 are end top sections. The top sections 25 are fixed to frame bars 27, and the said frame bars 27 are pivotally connected at 28 to the frame bars 7. The top sections 26 are fixed to 75 frame bars 29, and these frame bars 29 are pivotally connected at 30 to the frame bars 27. At their outer ends the frame bars 29 complementary to the top sections 26 are provided with pivoted rack bars 31, which 80 are designed to be extended through and engaged with the apertured plates 24 with a view to supporting the top sections 25 and 26 in inclined position as shown at the left of Fig. 1. It will be noticed here that the 85 top sections 25 and 26 at the opposite ends of the board can be simultaneously maintained in inclined position in order to so position a body that blood can be thoroughly drained therefrom, and a good circulation 90 of embalming fluid to all parts of the body can be attained. When the rack bars 31 are withdrawn from the apertured plates 24, the 95 said rack bars can be swung to positions alongside the frame bars 29 and secured by frictional contact under clips 32 provided on the said frame bars 29.

By breaking the struts 20 at one end of the board and letting down the extension frame bars 19, the frame bars 29 and one end 100 top section 26 the board can be adapted to support a short adult or a youth, while by breaking the struts 20 and letting down the extension frame bars 19, the frame bars 29 and the end top section 26 at both ends of 105 the board can be shortened to such an extent as to render it suitable to support the body of a child.

With the exception of the top sections 6, 110 25 and 26, which are made of thin wood bound with sheet-metal, the parts of my novel board are preferably of metal.

It will be gathered from the foregoing that when the board is set up and one top section 115 25 and one top section 26 are maintained in inclined position and the whole is covered with an ornamental cover the board will be transformed into a finished couch.

When desirable the couch may be provided with canopy supports 40, one of which is 120 shown in Figs. 1, 3, and 4. These canopy supports respectively comprise a bail shaped portion 41 having its ends socketed and secured in metallic fixtures 42, and any suitable means for attaching the said fixtures 42 to the end bars of the extension frames 19 of the board. The fixtures 42 are designed to rest flat on the end bars of the extension frames 19. In the preferred embodiment of my invention I prefer to pro- 130

vide each top section 26 with a transverse series of apertures 43. I also prefer to connect the fixtures 42 to the said end bars through the medium of bolts 44, extended 5 through the fixtures and apertures in the end bars of the extension frames 19. From this it follows that when it is not desired to use the canopy supports the same can be expeditiously and easily removed from the 10 board, and when it is desired to employ said supports the same can as readily be applied and connected to the frame extensions 19.

It will be understood from the foregoing that it is necessary precedent to folding the 15 board to swing each top section 26 and its complementary frame bars inwardly until each top section 26 rests parallel or approximately parallel with the adjacent top sections 6 and 25; each top section 26 also resting parallel to and closely adjacent the central leg 2. I would further have it understood that I prefer in practice to equip each 20 of the legs of the board with a rubber bottom or other pad 45.

I have entered into a detailed description 25 of the construction and relative arrangement of the parts embraced in the present and preferred embodiment of my invention in order to impart a full, clear and exact understanding of the said embodiment. I do 30 not desire, however, to be understood as confining myself to the said specific construc-

tion and relative arrangement of parts as in the future practice of my invention, such changes and modifications may be made as 35 fairly fall within the scope of my invention as claimed.

Having described my invention, what I claim and desire to secure by Letters-Patent, is:

A foldable embalmer's board, comprising top sections, frame bars, of right-angle form in cross-section, fixed to the undersides of the top sections adjacent the side edges of the board, said frame bars being arranged 45 in pairs and the bars of each pair being alined, arms fixed to the inner portions of the several frame bars, a transverse rod to the end portions of which said arms are pivotally connected, a leg connected to the 50 transverse rod at a point between the pairs of arms, transverse bars extending between and fixed to the frame bars, lugs fixed to and depending from said bars and having lateral bolts, and braces pivotally connected to the 55 leg and having apertures adapted to receive the bolts on the lugs.

In testimony whereof I have hereunto set my hand in presence of two subscribing witnesses.

CARL B. DOLGE.
